(57) CLAIM

The ornamental design for a cosmetic storage box, as shown and described.

DESCRIPTION

The parts shown by means of broken lines in the reproductions are not part of the claimed design; the dash dot dash lines in figure 1.1,1.2,1.11,1.12 and the number "1.11", "1.12" in figure 1.1,1.2 are for the purpose of depicting the cut line of the enlarged view and form no part of the claim.
